Attorneys.

UNITED STATES PATENT OFFICE.

LORENA C. MARSHALL, OF DENVER, COLORADO.

TENT COT.

Application filed April 22, 1922. Serial No. 556,007.

To all whom it may concern:

Be it known that I, LORENA C. MARSHALL, a citizen of the United States, residing at Denver, in the county of Denver and State 5 of Colorado, have invented certain new and useful Improvements in Tent Cots; and I do hereby declare the following to be a full, clear, and exact description of the invention, such as will enable others skilled in the art 10 to which it appertains to make and use the same.

This invention relates to tent cots, designed more particularly for automobilists, and has for its object to provide a combined 15 tent and cot which shall be free from bulky and complicated cot supporting mechanism and which can be manufactured at the minimum expense. The various features of novelty and invention will appear from the detailed description of the invention taken in 20 connection with the accompanying drawings forming part of the specification.

In the drawings,

Figure 1 is a plan view of the fabric 25 making up the tent and cot, the fabric being laid out flat;

Fig. 2 is a side elevation of the preferred form of the invention, and

Fig. 3 is a top plan view of the invention 30 as shown in Fig. 2.

In the drawings, 10 represents the cot portion, 11 the roof of the tent, 12 the flap or front closure member and 13 the side curtains or members. The cot portion 10 35 is provided with eyelets 14 around its marginal edges, there being at least one eyelet at each corner of the cot and preferably one at each side thereof, as shown. The cot is supported by stakes 15 which are driven into 40 the ground, the upper end of said stakes being of reduced diameter to form a shoulder on which the fabric may rest, it being understood that the eyelets are slipped over said reduced portions. I prefer to provide the 45 stakes with suitable braces 16 to prevent the same from tilting under the weight of the occupant.

The tent is provided with loops 17 at the

juncture of the flap 12 and wing-like portions 13 which form the side walls of the 50 tent. These loops may be secured to the fabric in any suitable manner as by stitching. The loops 17 are designed to form securing means for holding up the tent and may be attached to any suitable object, such as the 55 top of the automobile when the tent is used by automobilists, or they may be secured to trees or the like as will be readily understood.

The combined tent and cot may be made 60 from a single sheet of fabric laid out as shown in Fig. 1, although the invention is not limited to such one piece structure.

The manner of setting up the device will be readily understood from Fig. 2. The 65 stakes are first driven into the ground and the eyelets 14 slipped over the terminals of the same and the fabric then bent back upon itself as at a and extended upwardly, the loops being secured to any suitable object 70 as previously stated. In view of the fact that the cot portion is free from attached mechanism, the device may be folded up into a convenient bundle and stored away in any suitable compartment of the automobile. This feature is of considerable importance 75 since the storage of baggage space of automobiles is very limited.

What I claim is:

1. The combination of a tent cot, comprising integrally formed cot, top, side and end portions, a plurality of eyelets positioned at the corners of said cot portions, a plurality of supporting stakes having reduced end portions, said eyelets being adapted to set 80 over and engage said reduced end portions, and triangular bracing means cooperating 85 with said stakes for bracing and supporting the said cot portion from the ground.

2. The combination as in claim 1 and 90 reinforcing bracing loops carried at the upper corners of the top of the tent, adapted to be attached to suitable guying means.

In testimony whereof I affix my signature.

LORENA C. MARSHALL.
